LINER HANGER

Keith Ford, Long Beach, Calif., assignor, by direct and mesne assignments, of two-thirds to E. B. Hall, Los Angeles, Calif., and A. L. Armentrout, Long Beach, Calif., and one-third to V. P. Baker, Los Angeles, Calif.

Application January 16, 1939, Serial No. 251,055

1 Claim. (Cl. 166—1)

This invention relates to apparatus for use in wells and relates more particularly to a liner hanger for supporting or suspending a liner in a well. A general object of this invention is to provide a practical effective liner hanger that may be easily and successfully employed in situations where the conventional liner hangers are not operative or difficult to operate.

In conditioning an oil well for production it is the usual practice to arrange a tubular perforate liner in the producing zone to prevent caving, etc. A tool known as a liner hanger is employed to hang or suspend the liner in position in the well. The liner hanger is rigidly secured to the upper end of the liner and usually embodies slips for gripping the interior of the well casing and a tail-piece control for the slips having a latch means for governing the release and actuation of the slips. The latch means for controlling the hanger is usually releasable by rotation or turning movement of the entire liner and liner hanger. The assembly of the liner and the liner hanger is lowered into the well on a setting string and the string is rotated and manipulated to release the latch of the tail-piece and to set the slips of the hanger, whereupon the setting string is disconnected from the hanger and withdrawn from the well. In many instances the well bore is excessively inclined or crooked so that the liner binds on the wall of the well and is prevented from turning. Under such conditions it is difficult, if not impossible, to turn the setting string to effect the release of the latch means to condition the hanger for operation.

Another object of this invention is to provide a liner hanger that may be easily and quickly operated and set when the liner is non-rotatable by reason of the contour of the well.

Another object of this invention is to provide a liner hanger that may be conditioned and operated by any suitable setting tool, or the like.

Another object of this invention is to provide a liner hanger of the character mentioned that does not necessitate special or complicated manipulation of the setting string.

A further object of this invention is to provide a liner hanger of the character mentioned that is strong and dependable and that is simple and easy to manufacture and install on the liner.

The various objects and features of my invention will be fully understood from the following detailed description of a typical preferred form and application of the invention, throughout which description reference is made to the accompanying drawing, in which:

Fig. 1 is a longitudinal sectional view of a portion of a typical well showing the apparatus or equipment of the present invention in elevation prior to the setting or actuating of the liner.

Fig. 2 is a view similar to Fig. 1 illustrating the condition of the parts immediately following the actuation of the liner hanger and showing certain parts in longitudinal cross section, and Fig. 3 is an enlarged fragmentary longitudinal detailed sectional view of the swivel connection between the liner and the liner hanger.

The liner hanger of the present invention may be employed on liners of various natures and may be used in conjunction with setting tools of various types. In the following detailed description I will describe a typical preferred form of the invention used in combination with a typical well liner and a more or less conventional setting tool. It is to be understood that the invention is not to be construed as limited or restricted to the specific details about to be described but is to be taken as including any features or modifications that may fall within the scope of the claim.

The equipment or apparatus of the invention illustrated in the drawing may be said to comprise, generally, a liner L, a hanger H conditioned or released for operation by turning movement, a swivel joint or connection C between the hanger H and liner L and a setting tool T at the upper end of the hanger.

The liner L is an elongate perforated member or assembly adapted to be installed in the open producing portion of the well W to act as a screen. As the present invention is not primarily concerned with the details of the liner L, I have illustrated only the upper portion of the liner. It is to be understood that the liner L may be of substantial length and may embody a plurality of connected tubular sections. As illustrated, the liner L has perforations 10 for admitting the well fluid. The perforations 10 may be in the nature of slots. A suitable coupling or collar 11 may be threaded on the upper end of the liner L.

The liner hanger H is provided to engage or grip the interior of the well casing 12 and is operable to suspend the liner L from the casing 12. The hanger H includes an elongate tubular body 13 and a sleeve 14 shiftable longitudinally on the body. The lower portion of the sleeve 14 is tapered, being in the nature of a cone 15. A set of slips 16 is engaged about the cone 15 and is adapted to be actuated by the cone to grip the interior of the casing C. The outer sides of the slips 16 are toothed to have effective gripping engagement with the interior of the casing 12. When the slips 16 are in their un-actuated positions illustrated in Fig. 1 they are clear of the casing 12. Packing rings 17 may surround the hanger body 13 above the sleeve 14. The lower packing ring 17 may engage against the upper end of the sleeve 14. The upper packing ring 17 is shown engaged by the adapter 18 of the setting tool T.

tool T as will be hereinafter described. The packing rings 17 are adapted to be compressed to seal between the hanger body 13 and the internal surface of the well casing 12.

5 The liner hanger H includes a control for governing the release and actuation of the slips 16. This control includes spaced rings 19 surrounding and freely shiftable on the body 13 below the cone 15. Circumferentially spaced leaf springs 20 extend between and connect the spaced rings 19. The springs 20 are bowed outwardly to have frictional engagement with the interior of the well casing 12. Flexible resilient reins 21 are attached to the lower ends of the 10 slips 16 and have their lower ends secured to the uppermost ring 19 to connect the slips 16 with the spring and ring assembly 19-20. The engagement of the springs 20 with the casing 12 is operable to resist vertical movement of the slips 16 15 whereby downward movement of the hanger body 13 may cause the cone 15 to expand the slips into gripping engagement with the casing 12.

The control for the slips 16 further includes latch means for releasably connecting the assembly of the slips 16, the rings 19 and the springs 20 with the body 13 to prevent relative movement between the assembly and the body when the liner L is run into the well. The latch means includes one or more hook-like latches 22 on one of the rings 19. In the simple case illustrated there is a latch 22 depending from the upper ring 19. The latch 22 is cooperable with a radially projecting pin 23 on the body 13. The engagement of the latch 22 with the pin 23 serves 25 to prevent relative vertical movement between the body 13 and the assembly of the rings 19, the springs 20 and the slips 16. The latch 22 is such that the pin 23 is releasable from the latch by turning of the body 13 relative to the assembly of 30 the rings 19, the springs 20 and the slips 16. Following the release of the pin 23 from the latch 22 the body 23 is free to move downwardly with respect to the assembly of the rings 19, the springs 20 and the slips 16 to effect the actuation of the slips. 35 It is to be observed that the control for the slips 16 can be released only by relative turning between the body 13 and the assembly of the rings 19, the springs 20 and the slips 16.

The swivel joint or connection C serves to connect the body 13 with the liner L and is such that it permits turning of the body 13 relative to the liner L to release the pin 23 from the latch 22 in situations where the liner L is prevented from turning. The swivel connection C may be varied 50 considerably in character without departing from the broader aspects of the invention. In the structure illustrated the connection C includes two sections, namely, an upper section 24 and a lower section 25. The upper section 24 is connected with the hanger body 13. In the simple construction illustrated the section 24 is threaded on the lower end of the body 13. The lower portion 24a of the section 24 is reduced in external diameter providing the section with a downwardly facing annular shoulder 26. The lower section 55 25 of the connection C is connected with the upper end of the liner L. In the drawing the section 25 is shown threaded in the collar 11 on the upper end of the liner L. A socket 27 is provided in the upper end of the section 25 to receive the portion 24a of the section 24. The section portion 24a is freely rotatable in the socket 27. The connection sections 24 and 25 are tubular and the passage 28 through the sections 60 is preferably of the same fluid capacity as the

longitudinal opening 29 in the body 13 and the passage through the tubular liner L.

The sections 24 and 25 of the connection C are connected for relative rotation. In the form of the invention illustrated an annular ball groove 5 or race 30 is provided in the exterior of the portion 24a and an opposing or registering race 31 is formed in the wall of the socket 27. Balls 32 are arranged in the races 30 and 31 to connect the sections 24 and 25 against relative longitudinal 10 movement and disconnection. The balls 32 in the races 30 and 31 allow free relative turning between the sections 24 and 25. A radial opening 33 15 may be provided in the wall of the section 25 to admit the balls 32 to the races 30 and 31 when the connection C is assembled. A plug 34 may normally close the opening 33.

Packing means is provided to prevent the leakage of fluid from the connection C. Opposing annular grooves 35 are provided in the lower end 20 of the section 24 and the bottom wall of the socket 27 and a body or ring 36 of packing is received in the grooves 35. The packing ring 36 is effective in preventing the escape or passage of fluid between the sections 24 and 25. The packing means may further include a body or ring of packing 37 set in opposing annular grooves 38 25 in the shoulder 26 and the upper end of the section 25. The packing ring 37 prevents foreign matter from entering the connection C and assists in preventing the leakage of fluid from the connection. The packing rings 36 and 37 are 30 preferably formed of a material that is resistant to the action of the fluids in the well.

The invention may include means for initially 35 or normally connecting the sections 24 and 25 of the swivel connection C against relative turning so that the liner L is non-rotatably connected with the hanger H when the equipment is run into the well. This means for connecting the sections 24 and 25 against relative turning is 40 releasable or frangible and may be released or broken when the equipment is in the well W so that the body 13 may be turned with respect to the liner L to effect the release of the pin 23 45 from the latch 22 when the liner L is caught or held against rotation. The means for connecting the sections 24 and 25 against relative rotation may comprise a shear pin 39 set in a radial opening 40 in the wall of the section 25 and extending 50 into a socket 41 in the portion 24a. The shear pin 39 is designed to fail when subjected to a known or given shear strain.

The setting tool T is provided to releasably connect a setting string (not shown) with the 55 hanger H to facilitate the lowering of the hanger H and liner L into the well W, the settling or actuation of the hanger H and the removal of the hanger H and the liner L from the well. The setting tool T includes the adapter 18 mentioned 60 above. The adapter 18 is threaded on the upper end of the hanger body 13 and its lower end engages the upper packing ring 17. The adapter 18 is an elongate tubular member open at its opposite ends. Diametrically opposite reclining 65 T grooves or J grooves 43 are provided in the internal wall of the adapter 18. The main parts or arms of the grooves 43 are substantially vertical and extend to the upper end of the adapter 18. The grooves 43 are provided at their lower ends 70 with lateral portions 44 and vertical branches 45 extending upwardly and downwardly from the lateral portions 44. The setting tool T further includes a mandrel 46 connected with the lower end of the setting string (not shown). The 75

mandrel 46 is designed to enter the upper end of the adapter 18. Diametrically opposite lugs 47 are provided on the mandrel 46 to cooperate with the grooves 43. The lugs 47 are adapted to pass through the grooves 43 to the vertical branches 45. When the lugs 47 are in the branches 45 the hanger H and the liner L are non-rotatably connected with the member 46 and the setting string. By turning and shifting the mandrel 46 relative to the adapter 18 the lugs 47 may be disconnected from the grooves 43 to permit the detachment of the mandrel from the adapter 18 and the setting string from the mandrel, the hanger H and the liner L.

When the liner L is to be installed in the well W it is connected with the body 13 of the hanger H by the connection C and the setting tool adapter 18 is secured to the upper end of the hanger body 13. The mandrel 46 is connected with the adapter 18 by the engagement of the lugs 47 in the grooves 43 and the assembly is lowered into the well W on the lower end of the setting string (not shown). The assembly may be lowered until the liner L reaches the correct or selected position. The setting string (not shown) is then given a partial turn to release the pin 23 from the latch 22. The springs 20 frictionally engaging the interior of the casing 12 hold the rings 19 and the slips 16 against turning so that the turning of the body 13 may release the pin 23 from the latch 22. In the event that the well bore is excessively crooked the liner L may be engaged in the well in such a manner that it is non-rotatable. If this is the case it will be found difficult, if not impossible, to turn the setting string and liner L to effect the release of the pin 23 from the latch 22. If it is found that the latch pin 23 cannot be released from the latch 22 in the manner just described a substantial turning force is applied to the setting string (not shown) to shear or break the pin 39. It will be seen that the shear pin 39 serves to transmit turning forces from the hanger body 13 to the liner L and when a substantial turning force is imposed on the body 13 through the medium of the setting string and the tool T the pin 39 is sheared off or broken. Following the breaking of the pin 39 the setting string (not shown) may be given a partial rotation in the correct direction to disengage the pin 23 from the latch 22. At this time the body 13 is free to turn with respect to the liner L by reason of the swivel connection C and the caught or non-rotatable liner L does not interfere with the turning of the body 13 and the release of the pin 23 from the latch 22.

Following the release of the pin 23 from the latch 22 the setting string (not shown) may be lowered or allowed to settle so that the body 13 moves downwardly with respect to the slips 16. As described above the springs 20 engaging the liner L serve to resist downward movement of the slips 16 and the cone 15 moving downwardly with the body 13 expands or actuates the slips 16. The weight of the liner L and associated parts is imposed on the cone 15 through the medium of the adapter 18 and the packing rings 17 and the slips 16 gripping the casing 12 and engaging about the cone 15 suspends the liner from the casing 12. The weight of the liner L and associated parts transmitted through the packing rings 17 expands the rings into tight

sealing engagement with the interior of the casing 12 and holds the rings into effective sealing engagement with the body 13. Subsequent to the release and actuation of the slips 16 the setting string (not shown) may be manipulated to free the lugs 47 from the grooves 43 whereupon the mandrel 46 may be withdrawn from the adapter 18 and the setting string may be withdrawn from the well.

After a period of production of the well W it may be desirable or necessary to withdraw the liner L from the well W for replacement or repair. A well string carrying an adapter 18 is lowered into the well W and manipulated to enter the lugs 47 in the grooves 43 and to bring the lugs into the groove branches 45. The said string may then be raised to raise the body 13 and the liner L. Upward movement of the body 13 removes the weight of the liner L and associated parts from the slips 16 and the slips are free to retract from the casing 12. If desired or believed necessary the string (not shown) and the mandrel 46 may be turned to turn the body 13 and engage the pin 23 with the latch 22 to latch the slips 16 in their retracted positions so that the equipment may be withdrawn from the well without danger of the slips binding in the casing 12. In this connection it is to be observed that the swivel connection C allows free turning of the body 13 to re-engage the latch pin 23 with the latch 22 even though the liner L may be caught or sanded in the well W. Subsequent to the release or retraction of the slips 16 as above described the equipment may be withdrawn from the well W on the operating or removal string (not shown).

It will be noted that the present invention provides a liner hanger that is designed to permit the free easy release and control of the slips 16 in situations where the liner L may be non-rotatable due to the contour of the well. The swivel connection C provides for free turning of the hanger body 13 with respect to the liner and thus assures the easy and full control and manipulation of the liner hanger H during the setting and removal of the liner.

Having described only a typical preferred form and application of my invention I do not wish to be limited or restricted to the specific form and application herein set forth, but wish to reserve to myself any variations or modifications that may appear to those skilled in the art or fall within the scope of the following claim.

Having described my invention, I claim:

A hanger for suspending a liner in a well comprising a body having a cone, slips operable outwardly by the cone to grip the wall of the well, means holding the slips against operation releasable by turning of the body, means rotatably connecting the lower end of the body with the liner so that the body may be freely turned relative to the liner to release the first named means in the event the liner is non-rotatable in the well, and frangible means associated with the last mentioned means preventing relative rotation between the body and liner so that the liner may turn with the body when the liner is free for such turning and adapted to fail under a given rotational strain when the liner is non-rotatable in the well.

KEITH FORD.
